BELT BUCKLE

Harry Ganz, New York, N. Y., assignor to Bac-A-
Brand Products, Inc., New York, N. Y., a cor-
poration of New York

Application March 23, 1951, Serial No. 217,132

7 Claims. (Cl. 24—176)

1

The present invention is directed to belt buckles, more particularly to a buckle made of a single piece of material, such as molded plastic, metal or the like.

Belt buckles of various types have long been in use, some of them consisting of a number of parts which may be relatively movable. Such buckles are relatively expensive and as a result other constructions have been devised which are simpler and which are capable of accomplishing the desired result of holding a belt. However, in such constructions as previously known, one end of the belt was threaded through the buckle and stitched or riveted or otherwise fastened permanently to the buckle. While such a construction gave a satisfactory result, it had the disadvantage that additional labor was necessary in order to secure the end of the belt in position. Because the attachment was permanent, one could not conveniently remove the belt and replace it with another belt.

The present invention is intended and adapted to overcome the difficulties and disadvantages inherent in devices of the type described, it being among the objects of the present invention to provide a belt buckle which is unitary in construction and simple to manufacture.

It is also among the objects of the present invention to provide a belt buckle in which the end of a belt may be fastened so as to be securely held in place during normal use thereof without the necessity of applying any securing means thereto.

It is further among the objects of the present invention to provide a belt buckle which may be made of a suitable molded plastic material in a single operation without the necessity of providing complicated or expensive molds.

In practicing the present invention the belt buckle consists of a plate usually rectangular in shape and having a rectangular central opening therein. A bridge piece extends transversely of the opening so as to divide it into approximately equal spaces, the bridge piece being integral with the plate. On the rear face of the plate in the area of the bridge piece, a pair of transverse bars which are substantially parallel to each other are fixed. The bars are adjacent to the lateral edges of the bridge piece and at least one of the bars has a set of teeth or corrugations on the face thereof adjacent to the bridge piece. Preferably the buckle is molded in a single operation from a plastic substance. By this construction the end of a belt may be threaded under one of the bars and over the other bar whereby it is retained in

2

position. There is no danger of the belt slipping out of place as the tension of the belt when in use tends to more securely hold it in position on the bars.

5 In the accompanying drawing constituting a part hereof and in which like reference characters indicate like parts.

Fig. 1 is a front elevational view of a belt and buckle made in accordance with the present invention;

Fig. 2 is a longitudinal sectional view taken along line 2—2 of Fig. 1;

Fig. 3 is a rear elevational view of the buckle detached from the belt;

15 Fig. 4 is a longitudinal cross-sectional view of the buckle taken along line 4—4 of Fig. 3;

Fig. 5 is a transverse cross-sectional view thereof taken along line 5—5 of Fig. 4;

Fig. 6 is a view similar to Fig. 4, showing a 20 modified form of the invention;

Fig. 7 is a perspective view of a modified form, and

Fig. 8 is a cross-section of the upper part in Fig. 7, taken along line 8—8 of Fig. 7.

25 The belt buckle in its preferred form consists of a plate or frame having a pair of longitudinal members 1 and 2 and a pair of transverse members 3 and 4 forming a rectangle having a hollow portion or opening in the center. A transverse bridge piece 5 connects the central parts of members 1 and 2, dividing the opening into substantially equal parts 6 and 7. Extending inwardly from member 4 into space 7 is tongue 8 which is adapted to feed into holes in a belt for adjusting the same on the wearer.

As shown in Figs. 4 and 5, a transverse bar 9 is attached at its ends to legs 10 and 13 secured to the plate adjacent to one of the edges of bridge piece 5 and spaced downwardly therefrom, as shown in Fig. 5. A second bar 11 parallel to bar 9 has corrugations or teeth 12 on the inner face thereof. Legs 10 and 13 are attached to the ends thereof. In the form shown in Figs. 1—5 each of the end legs 10 and 13 is in the form of a wall, as best shown in Fig. 4. Bar 11 is secured adjacent to the opposite edge of bridge piece 5 and in a preferred form of the buckle, is slightly lower than bar 9 as shown in Fig. 4.

50 A belt 14 is threaded above bar 9, as viewed in Fig. 2, and is looped around bar 11 at 15 and threaded above bar 9, leaving a short end 16 extending therefrom. As tension is applied to belt 14, it forces end 16 against teeth 12, holding the belt firmly in position under all conditions of normal use. The free end 17 of the belt

3

has a series of holes 18 and it is threaded through space 7, with tongue 8 passing through one of the holes 18. The extreme end of the belt is extended under member 3 of the plate so as to hold it in position, all as shown in Fig. 2.

In Fig. 6 there has been shown a modification which is adapted for molding in a single operation. The buckle is provided with a transverse bar 19 having legs 20 terminating in members 1 and 2 of the plate. In this modification the end legs are not combined into a single wall. Bar 19 is parallel to the adjacent edge of bridge piece 5 so that a transverse plane at said adjacent edge will have bar 19 on one side and bridge piece 5 on the other side thereof. Similarly bar 21 having teeth 22 on the inner face thereof is held by legs 23 to members 1 and 2 of the plate. Bars 19 and 21 are substantially parallel to each other, and a transverse plane on the left hand edge of bridge piece 5 has bar 21 to the left thereof.

By such an arrangement the operation of the device is as effective as in the modification of Figs. 1 to 5. In molding the buckle in a single operation, the upper and lower parts of the mold may meet and define the entire area of the buckle without the necessity of having inserts, cores or other elements in the mold, which would render the mold expensive. The use of such a simple mold has the added advantage that the molding operation is speeded up, thus reducing labor costs. Because of the arrangement, bars 19 and 21 may be placed somewhat closer to bridge piece 5 than the bars shown in Fig. 4, while allowing ready threading of the belt thereon. Because of such closeness, there is a certainty that the belt when in position will be held securely.

In the modification shown in Figs. 7 and 8, the frame of the buckle is made in two parts. There is a base 24 having up-turned sides forming grooves 25 and which constitutes the front portion of a fabric covered buckle. The rear portion has the longitudinal sides 41 and 42 and ends 43 and 44, with depending sides 26 which fit into grooves 25. In completing the buckle, fabric is placed around member 24 and the upper member is forced into the same and crimped in place to hold the fabric.

A pair of bars 27 are formed integrally with the upper member, said bars being substantially parallel with bridge piece 45 and being spaced a substantial distance therefrom. The faces of bars 27 are raised above the general level of said upper member and usually about $\frac{1}{16}$ ". The sides 28 of bars 27 are formed so as to have corrugations therein. A belt may be threaded through said upper member, which is the back of the completed buckle, in the usual manner, whereby the corrugations hold the end of the belt firmly in position but permit adjustment thereof to any desired length.

Various changes in the details of construction of the new belt buckle may be made within the spirit of the invention. For instance, buckles of various sizes and shapes may be provided with the novel features described and claimed herein. Tongue 8 may be omitted in some forms of buckles. The height of the parallel bars may be changed and any type of serrations, corrugations or teeth may be provided.

These and other changes may be made in the details of the invention without departing from the principles herein set forth and the claims are,

therefore, to be broadly construed in accordance with the present invention.

I claim:

- 5 1. A one-piece molded plastic belt buckle for use with a thin belt comprising a plate having a central opening therein, a transverse bridge-piece integral with said plate dividing said opening into two parts, a stationary tongue projecting from one end of said buckle inwardly toward the bridge piece, first and second substantially parallel bars attached to the rear face of said bridge-piece and spaced therefrom, said bars being at the lateral edges of said piece, and serrations on the face of the second of said bars adjacent to said piece, whereby the end of a belt may be threaded over said first bar and around the other bar and then over the first bar to retain said belt on said buckle without the necessity of stitching said end of said belt.
- 15 2. A one-piece molded plastic belt buckle for use with a thin belt comprising a plate having a central opening therein, a transverse bridge-piece integral with said plate dividing said opening into two parts, first and second substantially parallel bars attached to the rear face of said bridge-piece and spaced therefrom, said bars being at the lateral edges of said piece, and serrations on the face of the second of said bars adjacent to said piece, whereby the end of a belt may be threaded over said first bar and around the other bar and then over the first bar to retain said belt on said buckle without the necessity of stitching said end of said belt.
- 25 3. A one-piece molded plastic belt buckle for use with a thin belt comprising a plate having a central opening therein, a transverse bridge-piece integral with said plate dividing said opening into two parts, first and second substantially parallel bars attached to the rear face of said bridge-piece and spaced therefrom, said bars being at the lateral edges of said piece, and serrations on the face of the second of said bars adjacent to said piece, said second bar being spaced from said piece a greater distance than the other bar, whereby the end of a belt may be threaded over said first bar and around the other bar and then over the first bar to retain said belt on said buckle without the necessity of stitching said end of said belt.
- 30 4. A one-piece molded plastic belt buckle for use with a thin belt comprising a plate having a central opening therein, a transverse bridge-piece integral with said plate dividing said opening into two parts, a stationary tongue projecting from one end of said buckle inwardly toward the bridge piece, first and second substantially parallel bars attached to the rear face of said bridge-piece and spaced therefrom, the points of attachment being at the junctions of said piece and said plate, said bars being at the lateral edges of said piece, and serrations on the face of the second of said bars adjacent to said piece, whereby the end of a belt may be threaded over said first bar and around the other bar and then over the first bar to retain said belt on said buckle without the necessity of stitching said end of said belt.
- 40 5. A one-piece molded plastic belt buckle for use with a thin belt comprising a plate having a central opening therein, a transverse bridge-piece integral with said plate dividing said opening into two parts, first and second substantially parallel bars attached to the rear face of said bridge-piece and spaced therefrom, the points of attachment being at the junctions of said piece and said plate, said bars being at the lateral edges of said piece, and serrations on the face of the second of said bars adjacent to said piece, whereby the end of a belt may be threaded over said first bar and around the other bar and then over the first bar to retain said belt on said buckle without the necessity of stitching said end of said belt.
- 45 6. A one-piece molded plastic belt buckle for use with a thin belt comprising a plate having a central opening therein, a transverse bridge-piece integral with said plate dividing said opening into two parts, first and second substantially parallel bars attached to the rear face of said bridge-piece and spaced therefrom, said bars being at the lateral edges of said piece, and serrations on the face of the second of said bars adjacent to said piece, said bars extending laterally beyond the lateral edges of said piece, whereby the end of a belt may be threaded over said first bar and around the other bar and then over the first bar to retain said belt on said buckle without the necessity of stitching said end of said belt.
- 50 7. A one-piece molded plastic belt buckle for use with a thin belt comprising a plate having a central opening therein, a transverse bridge-piece integral with said plate dividing said opening into two parts, a stationary tongue project-

ing from one end of said buckle inwardly toward the bridge piece, first and second substantially parallel bars attached to the rear face of said bridge-piece and spaced therefrom, said bars being at the lateral edges of said piece, and serrations on the face of the second of said bars adjacent to said piece, said plate having a convex curvature, said bars being contained within the space defined by said plate and the plane between the ends of said plate at the rear thereof, whereby the end of a belt may be threaded over said first bar and around the other bar and then over the other bar to retain said belt on said buckle without the necessity of stitching said end of said belt.

6. A one-piece molded plastic belt buckle for use with a thin belt comprising a plate having a central opening therein, a transverse bridge-piece integral with said plate dividing said opening into two parts, first and second substantially parallel bars attached to the rear face of said plate on opposite sides of said bridge-piece and spaced therefrom, said bars being at the lateral edges of said piece, and serrations on the face of the second of said bars adjacent to said piece, whereby the end of a belt may be threaded over said first bar and around the other bar and then over the first bar to retain said belt on said buckle without the necessity of stitching said end of said belt.

7. A one-piece molded plastic belt buckle for use with a thin belt comprising a plate having

a central opening therein, a transverse bridge-piece integral with said plate dividing said opening into two parts, a stationary tongue projecting from one end of said buckle inwardly toward the bridge piece, first and second substantially parallel bars attached to the rear face of said plate on opposite sides of said bridge-piece and spaced therefrom, said bars being at the lateral edges of said piece, and serrations on the second of said bars adjacent to said piece, whereby the end of a belt may be threaded over said first bar and around the other bar and then over the first bar to retain said belt on said buckle without the necessity of stitching said end of said belt, said serrations being corrugations in the side of said bar.
